F. W. SHUMAN

SEAT

Filed Aug. 11, 1921

Patented July 8, 1924.

1,500,338

UNITED STATES PATENT OFFICE.

FREDERICK W. SHUMAN, OF SOUTH BEND, INDIANA.

SEAT.

Application filed August 11, 1921. Serial No. 491,467.

To all whom it may concern:

Be it known that I, FREDERICK W. SHUMAN, a citizen of the United States, and a resident of South Bend, in the county of 5 St. Joseph and State of Indiana, have invented certain new and useful Improvements in Seats; and I do hereby declare the following to be a full, clear, and exact description of the invention, such as will enable others skilled in the art to which it 10 pertains to make and use the same.

This invention relates to improvements in seats and more particularly to such as are adapted for use in a swing construction— 15 one object of the invention being to provide a seat or swing which shall be sufficiently flexible that it will readily adapt itself to the contour of the body of the user thereby insuring comfort to the user.

20 A further object is to so construct the seat or swing that it may be readily assembled or taken apart and packed in small space for shipment or storage.

25 A further object is to provide a seat or swing which shall be simple in construction, economical to manufacture and which shall be substantial.

With these and other objects in view, the 30 invention consists in certain novel features of construction and combinations of parts as hereinafter more fully described and pointed out in the claims.

In the accompanying drawings, Figure 1 35 is a side elevation of the seat equipped for use as a swing, embodying my improvements. Fig. 2 is a front elevation and Figs. 3 and 4 are fragmentary views.

The bottom and back portions 1—2 of the 40 device each comprises a plurality of slats 3 having perforations near their respective ends for the passage of flexible metal rods 4—5 respectively, and the slats of the bottom and back members are spaced apart by suitable blocks 6 having perforations for the 45 passage of the flexible rods. The bottom and back members are separated as at 7 and these separated portions are connected by means of springs 8 which serve to add flexibility to the structure. The end portions or respective rods 4—5 at the point 7 pass through 50 the members of the spring 8 and are threaded to receive nuts 9.

The back number 2 of the device is provided at its top with an enlarged slat or rail 55 10 which is perforated for the accommodation of the upper ends of the rods 5 and is

made with a countersink 11 to receive a head 12 at the upper end of each of said rods. Two of the slats which constitute parts of the back member of the seat or swing and 60 which are located near the lower end of said back member are made with extensions 3^a projecting beyond the ends of the slats 3 above and below the same. Between the slat extensions 3^a the back ends of arm rests 65 13 are disposed and secured in place by means of bolts 14—said bolts being threaded at their lower ends for the reception of nuts 15 and provided at their upper ends with eyes or hooks 16 for a purpose hereinafter 70 explained. Between the front portions of the arm rests 13 and the front ends of the bottom member 1 of the seat, posts 17 are located. These posts may extend downwardly slightly past the front slat 3^b of the 75 bottom member and is secured to the latter by transverse bolts 18 passing through the posts 17 and said front slat. The bolts 18 also pass through a front bottom rail or slat 19 and the latter is made with a countersink 80 20 to receive the head of said bolt—the other end of the bolt near each end of the front bottom rail is threaded to receive a nut 21. A rod 22 passes downwardly through a suitable hole in each arm rest 13 and extends 85 through a suitable hole in the front slat 3^b of the bottom member. The lower ends of the rods 22 are threaded to receive nuts 23 and the upper ends of said rods are provided 90 with eyes or hooks 24.

From the construction and arrangement of parts above described, it is evident that the various members may be quickly and securely assembled and produce a structure which will be sufficiently flexible to insure 95 comfort to the user and at the same time be substantial and capable of sustaining any weight required in ordinary use. It is equally evident that the various members may be dis-assembled and the structure in 100 knock-down condition, packed in small space for shipment or storage.

The eyes or hooks 16—24 at the upper ends of the rods or bolts 14 and 22 receive the lower ends of chains 25—25—the upper 105 ends of the latter being connected with supporting chains 26 whereby the structure will be adapted for use as a porch swing.

Various slight changes might be made in the details of construction of my invention 110 without departing from the spirit thereof or limiting its scope and hence I do not wish

to restrict myself to the precise details herein set forth.

Having fully described my invention what I claim as new and desire to secure by Letters Patent, is:

1. A device of the character described having back and bottom portions comprising slats, spaced apart, flexible rods passing through holes near respective ends of the 10 slats, one end of each of said rods provided with a head, a nut threaded on the other end of each of said rods, some of the slats near the lower edge of the back portion being extended beyond the side edges of the back 15 portion, arm rests secured to said projecting end portions of said slats, supporting posts for said arm rests, the front slats of the bottom member being extended beyond the side edges of the bottom member, means for securing the lower ends of the posts to the extended ends of said front slats, and means for securing the front ends of the arm rests upon the upper ends of the posts.

2. A device of the character described

comprising flexible back and bottom members, each consisting of a plurality of spaced slats, rods securing said slats in assembled positions, two of the slats of the back member projecting at respective ends beyond the planes of the ends of the other slats of said back member, arm rests having their back ends disposed between said projecting slats, and fitted on the rods passing through said slats, bolts passing through the arm rests and said projecting slats, supporting posts for the arm rests, means securing said supporting posts to the front portion of the bottom member and suspending means connected to the last-mentioned means and to the bolts passing through the arm rests and the projecting ends of the slats.

In testimony whereof, I have signed this specification in the presence of two subscribing witnesses.

FREDERICK W. SHUMAN.
